UNITED STATES PATENT OFFICE.

JAMES BOBBET VON CANON, OF WEST END, NORTH CAROLINA.

SELF-LOADING MECHANISM FOR VEHICLES.

Application filed October 26, 1921. Serial No. 510,570.

To all whom it may concern:

Be it known that I, JAMES BOBBET VON CANON, a citizen of the United States, and a resident of West End, in the county 5 of Moore and State of North Carolina, have invented certain new and useful Improvements in Self-Loading Mechanism for Vehicles, of which the following is a specification.

10 My invention relates to self-loading vehicles such as embodied in my Patent No. 1,397,993, Nov. 22, 1921, and more particularly to the mechanism for loading vehicles with comminuted materials such as gravel, 15 sand, and the like.

The purpose of my invention is the provision of a loading mechanism which is applicable to any standard form of dumping vehicle, and which includes endless chains 20 of constantly moving buckets adapted to be automatically actuated to successively occupy scooping, loading and dumping positions at proper intervals to scoop the material to be loaded from a point beneath 25 the vehicle and to convey such material to and above the vehicle body where it is dumped into the body. My invention further provides a carriage for supporting the chain of buckets which is adjustable to 30 vary the scooping position of the buckets so that they may collect materials disposed at different levels beneath the vehicle.

I will describe one form of vehicle and one form of loading mechanism embodying 35 my invention and will then point out the novel features thereof in claims.

In the accompanying drawings:

Figure 1 is a view showing in side elevation a dumping vehicle having applied 40 thereto one form of loading mechanism embodying my invention.

Figure 2 is an enlarged detail perspective view of one of the buckets comprised in the loading mechanism shown in Figure 1.

45 Figure 3 is a transverse sectional view of the bucket shown in Figure 2.

Figure 4 is an enlarged perspective view of the carriage comprised in the loading mechanism shown in Figure 1.

50 Similar reference characters refer to similar parts in each of the several views.

Referring specifically to the drawings and particularly to Figure 1, I have here shown a dumping vehicle having a body B constructed in a manner similar to the body of the self-loading vehicle embodied in my ap-

plication hereinbefore referred to. This body is so constructed as to allow the dumping of its contents from the sides of the body, the material gravitating downwardly and outwardly of the body because of inclined inner walls comprised in the body. The body B is arranged upon the chassis C of the vehicle and is provided with suitable openings to receive portions of the elevating mechanism, one of the openings being bordered by a flange or collar F as clearly shown in Figure 1.

The loading mechanism forming the subject matter of the present invention comprises in its present embodiment a carriage designated generally at K, and which, as shown in Figure 4, comprises a U-shaped frame 15 fulcrumed adjacent one end upon a shaft 16 to permit rocking movement thereof through the medium of an actuating lever 17 provided with a spring pressed dog 18 adapted to engage a segmental rack 19 for locking the frame in any adjusted position. The free ends of the frame 15 carry an axle 20 which works in the slotted upper ends of a pair of bars 21. Within the slots of the bars 21, expandable springs 22 are arranged so as to engage the opposite sides of the axle 20 and thus urge the latter to a point medially of the ends of the slots. The lower ends of the bars 21 carry pins or bolts 23 which work in the slotted upper ends of bars 24, such pins or bolts being releasable to allow of the longitudinal adjustment of 90 the bars 24 to the bars 21. The lower ends of the bars 24 are formed with ears 24a in which is supported an axle 25. Also connected to the axle 25 are extensions 26 formed on the lower ends of a pair of channel bars A which extend upwardly in the direction of the frame 15 where they are provided with other extensions 27 formed with bearings 27a which embrace the shaft 16.

In the applied position of the carriage K upon the body B of the vehicle, the shaft 16 is journaled in a pair of brackets T supported on the body at opposite sides of the flange F. The frame 15 is arranged above the body by virtue of its mounting on the shaft with its free ends extending to the rear end of the body B. The bars 21 and 24 are disposed at the rear end of the body and extend downwardly to a point beneath the chassis C. The channel bars A extend upwardly through suitable openings formed

in the body and through the flange opening F at the top of the body where they are connected to the shaft 16 in the manner previously described.

As shown in Figure 1 and as indicated in dash lines in Figure 4, an endless chain N is trained about a sprocket 28 keyed to the shaft 16, a sprocket 29 loosely mounted on the axle 25, and a third sprocket 30 loosely mounted on the axle 20. The sprocket 29 is confined at a definite point on the axle 25 by means of keyed collars 32 as clearly shown in Figure 4. The chain N carries at regular spaced intervals a plurality of transversely arranged yokes 33, upon each of which is pivotally sustained a bucket E by means of bolts 34 in the manner clearly shown in Figures 2 and 3. Secured to the sides of each bucket at a point adjacent two corners thereof are angle irons 35 which are of such a length as to have portions thereof projecting to the lower side of the bucket as when viewed in Figure 2. These angle irons 35 are adapted to work within the channel bars A for sustaining the bucket in upright position, and consequently the arrangement of the channel bars is such that during rotation of the endless chains, the angle irons of the several buckets successively move into and out of the channel bars during the upward movement of the buckets.

For actuating the endless chain N, I utilize the engine of the motor vehicle and operatively connect the latter to the shaft 16 through the following mechanism: As shown in Figure 1, a shaft 36 is journaled in suitable brackets 37 supported on the body B, with the forward end of the shaft provided with a chain and sprocket connection to the shaft of the engine as indicated at 38. This connection is normally ineffective to drive the shaft 36 but is adapted to be operatively connected thereto by means of a clutch 39 operable by a lever 40 arranged in convenient position with respect to the driver's seat of the vehicle. The rear end of the shaft 36 is operatively connected to the shaft 16 through the medium of a worm 41 and a worm gear 42.

Referring now to Figures 2 and 3, it will be seen that each bucket E is formed with a forward scooping edge 43 that is arranged on a bias for the purpose of securing a shearing cut as the bucket penetrates the material to be elevated. This prevents the possibility of the bucket becoming clogged in the material so that the proper operation of the mechanism is insured.

As shown in Figures 1 and 4, the axle 25 pivotally supports at its opposite ends a pair of extension 44 formed on a pair of shoes S, such extension being locked against displacement on the axle by means of collars 45. As shown in Figure 4, the confronting sides of the shoes S are formed with flanges

46 having concaved upper edges 46^a over which the buckets E are adapted to move in such manner that the flanges serve to accurately guide the buckets from a dumping position to a scooping and subsequently to a loading position.

In the operation of the loading mechanism, the vehicle is adapted to overlie the material to be loaded and in such manner that the shoes S are disposed at the rear of the material. By an actuation of the clutch 39, the chain N and the buckets E are set in motion so as to continuously move in the direction indicated by the arrows in Figure 1. As the buckets move downwardly into engagement with the guide flanges 46 of the shoes S, they scoop the material to be loaded, and during such operation the flanges 46 function to move the buckets to scooping position whence they are filled and then to loading position to prevent discharge of the material from the buckets. After leaving the flanges, the buckets are maintained in loading position by the angle irons 35 moving into the channel bars A so that during the upward movement of the buckets they are maintained in loading position until the angle irons pass out of the channel bars which is at a point directly above the flange F. At this instant the material contained in the buckets serves to gravitate the latter to a dumping position as clearly shown in Figure 1 which is permitted by virtue of the pivotal mounting of the buckets. With the buckets in dumping position, the material is deposited into the body B of the vehicle. During the continued movement of the buckets upwardly over the sprocket 28, they are thrown under the action of the centrifugal force created by the rapid movement of the buckets around the sprocket to such a position that the angle irons are disposed in parallelism to the chain N. After leaving the sprocket 29, the buckets E are maintained in the position just described so that they are again in position to effect the scooping of the material as they pass between the shoes S.

If, during the operation of the mechanism, it is found necessary to re-position the shoes S in the path of travel of the buckets in order to effectively scoop the material, the entire mechanism can be shifted to the position desired through a manipulation of the lever 17. By moving the lever 17 upwardly or downwardly, a corresponding movement of the rear end of the frame 15 is effected, the latter swinging about the shaft 16 as a center. When the rear end of the frame 15 is moved upwardly or downwardly, a similar movement of the shoes S takes place, with the channel bars shifting to maintain triangular formation of the carriage so as to insure the proper operation of the chain and buckets. When the mechanism is not in use,

the shoes and adjacent parts can be elevated a distance sufficient to permit of free movement of the vehicle over the ground without the latter engaging the mechanism.

5 It is to be particularly noted that during the operation of the mechanism, the springs 22 serve to resiliently support the bars 21 and 24 whereby, a limited vertical movement of the lower part of the mechanism is permitted so that should the shoes engage an impassable obstacle such as a stone or the like they can move upwardly a distance sufficient to move over the obstacle. The adjustability of the bars 21 and 24 permits an 15 adjustment of the carriage to take up any slack in the chain N, while the pivotal mounting of the shoes allows them to conform to any irregularity or unevenness in the material over which they are moving.

20 Although I have herein shown and described only one form of loading mechanism embodying my invention, it is to be understood that various changes and modifications may be made herein without departing from 25 the spirit of the invention or the spirit and scope of the appended claims.

What I claim is:

1. In combination, a vehicle and a self-loading mechanism on said vehicle comprising 30 an adjustable carriage, an endless chain movably supported on the carriage, a plurality of buckets mounted on the chain to occupy loading and dumping positions and normally occupy dumping positions, coacting 35 means on the buckets and on said carriage for causing the buckets to occupy loading position during upward travel of the buckets to a predetermined point and then dumping position, and means for adjusting 40 the carriage to cause the loading mechanism to occupy various positions with respect to the vehicle and shoes supported on the carriage having flanges arranged to be engaged by the buckets for moving the latter to 45 scooping position and subsequently to loading position.

2. In combination, a vehicle, and a self-loading mechanism on said vehicle, comprising 50 an adjustable carriage including channel bars, a chain mounted for continuous movement around the carriage, a plurality of buckets pivotally supported on the chain to occupy scooping, dumping and loading positions and normally occupying dumping 55 positions, angle irons secured to the buckets and adapted to slidably engage said channel bars for maintaining the buckets in loading positions for a portion of their upward travel from the carriage, means supported 60 on the carriage for moving the buckets to scooping and subsequently into loading positions and means for adjusting the carriage to cause the loading mechanism to occupy various positions with respect to the vehicle 65 and shoes supported on the carriage having

flanges arranged to be engaged by the buckets for moving the latter to scooping position and subsequently to loading position.

3. A self-loading mechanism for vehicles comprising a carriage including channel bars, a chain mounted for continuous movement around the carriage, a plurality of buckets pivotally supported on the chain to occupy scooping, dumping and loading positions and normally occupying dumping positions, angle irons secured to the buckets and adapted to slidably engage said channel bars for maintaining the buckets in loading positions for a portion of their upward travel from the carriage, and shoes supported on the carriage having flanges arranged to be engaged by the buckets for moving the latter to scooping positions and subsequently to loading positions.

4. In combination, a vehicle including a body 85 including a carriage adjustably supported on the body and having channel bars extending through the body, an endless chain mounted for movement around the carriage, a plurality of buckets pivotally supported on the chain and capable of occupying scooping, loading and dumping positions and normally occupying dumping positions, angle irons secured to the buckets and adapted to travel through said channel bars for maintaining 90 the buckets in loading positions when loaded, and shoes pivotally supported at the lower end of the frame to occupy various positions to facilitate the collecting of material, said shoes being formed with concaved flanges 100 adapted to move the buckets to scooping positions and subsequently to loading positions.

5. A loading mechanism for vehicles comprising a carriage including a frame adapted to be mounted for pivotal movement, extensible bars resiliently and pivotally supported on the frame, a pair of channel bars pivotally connected to the frame and to said bars, shoes supported on the lower end of the frame for pivotal movement, a chain 110 mounted for movement around the frame, buckets pivotally supported on the frame to occupy dumping, loading and scooping positions, and normally occupying dumping positions, angle irons carried by the buckets 115 adapted to move through said channel bars to maintain the buckets in loading position, and flanges formed on the shoes and adapted to engage said buckets for moving the latter to scooping position and subsequently to 120 loading position.

6. In combination, a motor vehicle including a body formed with openings and a shaft supported above the body and adapted to be operatively connected to the motor of the 125 vehicle, and a loading mechanism comprising a carriage including a frame pivotally supported on said shaft and extending to the rear of said body, a shaft carried by the rear end of said frame, extensible bars resili-

ently supported on said shaft and extending to a point beneath and in the rear of said body, a second shaft carried by the lower ends of said bars, channel bars extending 5 through the openings of said body and pivotally connected to the body shaft and to said second shaft, sprockets on all of said shafts, a chain trained about said sprockets, buckets pivotally connected to said chain to 10 occupy scooping, loading and dumping positions, and normally occupying dumping positions, angle irons carried by the buckets and adapted to move through said channel bars to maintain said buckets in loading positions, shoes pivotally supported on said second shaft and having flanges adapted to engage said buckets for moving the latter to 15 scooping positions and subsequently to loading positions, and coacting means supported 20 on said body and connected to said frame for adjusting said carriage to cause the loading mechanism to occupy various positions with respect to the vehicle.

7. In combination, a motor vehicle including 25 a body formed with openings and a shaft supported above the body and adapted to be operatively connected to the motor of the

vehicle, and a loading mechanism comprising a carriage including a frame pivotally supported on said shaft and extending to 30 the rear of said body, a shaft carried by the rear end of said frame, extensible bars resiliently supported on said shaft and extending to a point beneath and in the rear of said body, a second shaft carried by the 35 lower ends of said bars, channel bars extending through the openings of said body and pivotally connected to the body shaft and to said chain to occupy scooping, loading and dumping positions, and normally 40 occupying dumping positions, angle irons carried by the buckets and adapted to move through said channel bars to maintain said buckets in loading positions, shoes pivotally supported on said second shaft and having 45 flanges adapted to engage said buckets for moving the latter to scooping positions and subsequently to loading positions, a rack bar supported on the body, and a lever connected to said frame and having a pawl engageable 50 with said rack bar for the purpose described.

JAMES BOBBET VON CANON.
